UNITED STATES PATENT OFFICE

RUSSELL J. ANDERSON, OF RACINE, WISCONSIN, ASSIGNOR TO BELLE CITY MALLEABLE IRON COMPANY, OF RACINE, WISCONSIN, A CORPORATION OF WISCONSIN

SKIMMING TOOL

Application filed August 15, 1930. Serial No. 475,481.

The present invention is in a skimming tool for use in skimming off or removing slag and surface impurities from a bath of molten metal. The life or period of usefulness of 5 skimmers is short because of the high heat to which they are subjected in use, resulting in oxidation of the tool and eventual destruction thereof. This necessitates frequent expensive replacement.

10 More particularly then, the invention relates to an improved skimmer which will not burn out and become destroyed.

The primary object of the invention is to provide an improved skimming tool having 15 means to cause circulation therethrough of a cooling liquid when the same is in use, whereby such liquid acts as a heat transfer agent to protect the skimmer.

Another object is generally to improve 20 skimmers of the kind mentioned.

Briefly these desirable objects are achieved in this embodiment of the invention by the provision of a skimming tool comprising a hollow skimmer head and a hollow shaft connected thereto, said shaft in turn carrying a handle. Arranged within the shaft is a conduit for leading a cooling liquid into the head for circulation therethrough, the heated liquid then by-passing around the inlet conduit through the shaft to be discharged, at 25 any appropriate point. So much will at this time suffice to give a general view of the improved structure.

In the accompanying sheet of drawings illustrating a practicable embodiment of the 30 invention:

Figure 1 is a general plan view of the skimmer;

Figure 2 is a side elevational view thereof;

40 Figure 3 is an end view of the head; and,

Figure 4 is a cross sectional view through the shaft as seen along the section line 4—4 appearing in Figure 1, as viewed in the direction of the arrows.

45 The skimmer shown embodies a hollow shaft 10 preferably in the form of a pipe which at one end has welded thereto a handle 11. The other end of the shaft 10 is in communication with a rectangular or box shaped, 50 closed skimmer head 12, the shaft being pref-

erably welded to said head at the central point thereof, midway between its ends. A water (or other cooling liquid) inlet conduit 13 in the form of a pipe from an exterior point is passed with a tight joint through the shaft 10 into the interior thereof, said conduit 13 then arranged axially inside the shaft and spaced therefrom a distance radially inward to leave a circulatory passageway 14 which communicates with the interior of the head 12. That part of the conduit 13 near the head is best supported and maintained in proper position by supports 15 of a kind which will least obstruct the passageway 14. It is important to observe that the conduit 13 has its discharge end extended a substantial distance into the head 12. A control valve 16 is associated with the conduit 13 as shown in Figure 2. An outlet lead 17 is also provided in communication with the passageway 14.

In use the conduit 13 is connected to a cooling liquid source under pressure. The tool is next located in the melting furnace with the same ready to skim slag from the 75 surface of the melted metal. The valve 16 has been opened and the cooling liquid then passes into the head and because of the extension of said conduit into the head 12 the liquid is caused to wash the walls of the head 80 in a most thorough manner, the liquid passing to opposite ends of the head, as shown by the arrows in Figure 2, and thence into the passageway 14 to be carried off by the outlet lead 17 in an obvious manner. Thus the 85 liquid quickly transfers the heat to cool the skimmer in an effective manner to protect the same against burning out.

From this detailed description it is now apparent that an improved skimmer results 90 which achieves the objects heretofore recited and that the same is simple and cheap to produce with no likelihood that the same will get out of order.

It is the intention to cover all such changes 95 and modifications of the form of the invention herein disclosed which do not in material respects depart from the invention as expressed within the scope of the following claims.

What I claim is:

1. In a skimmer, a closed hollow skimmer head, a hollow shaft connected thereto and in communication therewith, a conduit arranged axially within the shaft in a manner to provide a passageway between it and the shaft, said conduit communicating with the interior of the head, and an outlet from the passageway into said head.
- 10 2. In a skimmer, a closed hollow skimmer head, a hollow shaft connected thereto and in communication therewith, a conduit arranged axially within the shaft in a manner to provide a passageway between it and the shaft, said conduit communicating with the interior of the head and extending a distance into said head, and an outlet from the passageway into said head.
- 20 3. In a skimmer, an elongated closed hollow skimmer head, a hollow shaft secured to the head midway between its ends, said shaft communicating with the interior of the head, and an inlet conduit into said head arranged inside and axially of the shaft in a manner to provide an outlet passageway from the head between the shaft and conduit.
- 25 4. In a skimmer, an elongated closed hollow skimmer head, a hollow shaft secured to the head midway between its ends, said shaft communicating with the interior of the head, and an inlet conduit arranged inside and axially of the shaft in a manner to provide an outlet passageway from the head between the shaft and conduit, said conduit extending
- 30 35 a substantial distance into the head.
- 35 5. A skimmer comprising a hollow rectangular head, a shaft comprising a pipe connected to the head intermediately of its ends and communicating with the interior of the head, a second and smaller pipe inside the first pipe, said smaller pipe also communicating with the head interior and extending part way into said head, said inner pipe serving as a cooling liquid inlet and a space between the two pipes serving as an outlet.
